UNITED STATES PATENT OFFICE.

LILI ALINE McGRATH, OF BROOKHAVEN, MISSISSIPPI.

FLOOR-POLISHER.

1,136,150.

Specification of Letters Patent. Patented Apr. 20, 1915.

Application filed June 9, 1914. Serial No. 843,986.

To all whom it may concern:

Be it known that I, LILI ALINE McGRATH, a citizen of the United States, and a resident of Brookhaven, in the county of Lincoln and State of Mississippi, have invented certain new and useful Improvements in Floor-Polishers, of which the following is a specification.

My invention relates to the polishing of floors, and the main object thereof is to provide means for accomplishing this result in a pleasurable manner.

A further object is to provide such means which utilize the weight of a person using the same.

A further object is to provide such means in the shape of foot coverings, such as slippers, adapted to be worn by the user.

A further object is to provide means there-
20 with insuring safety to the wearer against falls on the polished surface; and further objects are to provide such devices which are simple in construction and use, highly efficient, and comparatively inexpensive.

25 My invention is fully described in the following specification, of which the accompanying drawings form a part, in which the separate parts are designated by the same reference characters in each of the views, and in which:—

Figure 1 is a partial view of a person using my invention; Fig. 2 is an enlarged view of the invention, ready for use; Fig. 3 is an enlarged section taken on the line 3—3
35 of Fig. 2; and Fig. 4 is an enlarged section taken on the line 4—4 of Fig. 2.

In the drawings forming a part of this application I have shown a present preferred form of my invention, comprising a pair of slippers $a-a$, composed of a leather or fabric member a^2 turned to form a heel loop a^3 , and which member is shaped to fit the foot of a person intending to use the device, and an insert a^4 is provided which is carried upwardly to form the upper of the slipper, and I also provide a bottom member a^5 forming the sole and heel of the slipper and composed of some suitable polishing material, relatively soft, the material of

which it is composed and the texture being 50 in accordance with the particular use for which the device is intended, as the polishing of varnished floors requires a different material than the polishing of waxed or oiled floors, but the exact material is not 55 herein claimed.

I prefer to make the slippers sufficiently large to permit the wearer to use the same with his or her usual foot coverings, although this is not necessary, and I will also 60 connect the slippers of each pair with a stout cord or twine b , passed through the corresponding loops a^3 provided for this purpose, and by means of which the slippers may also be suspended when not in use, and 65 this cord is made of a length permitting a full stride of the wearer, as in dancing, but not sufficiently long to admit of the wearer's feet spreading apart to permit his or her fall, and this is an important part of the 70 invention.

The operation is obvious:—The wearer merely places his or her feet within the slippers and begins to dance, preferably such dances as require long glides, and it will 75 be seen that the floor polishing operation becomes a pleasure and, also, the entire weight of the wearer is utilized instead of merely the weight of the upper part of the body when the floors are polished in a kneeling 80 position, the usual manner.

My invention is very simple, though well adapted to the purpose for which it is designed, and I may make the same of any desired form, and of any desired material, 85 and other changes in and modifications of the construction shown and described may be made, within the scope of the following claim, without departing from the spirit of my invention, or sacrificing its advantages, and, reserving the right to all such changes.

What I claim as new, and desire to secure by Letters Patent, is:—

A floor polishing device, comprising a 95 pair of foot coverings, each of which comprises a strip of suitable material bent intermediate its ends to form superimposed

sole members having a loop at the bend, a slipper upper having the lower edges thereof tucked between said sole members, a bottom member also held between said sole members, said upper and sole members being secured together forwardly of said loop, and a cord joining said loops.

In testimony whereof I have signed my name to this specification in the presence of the subscribing witnesses.

MRS. LILI ALINE McGRATH.
